UNITED STATES PATENT OFFICE.

JOSEPH M. HARTLEY, OF PHILADELPHIA, PENNSYLVANIA.

APPARATUS FOR SCORING FOOTBALL GAMES OR THE LIKE.

Application filed October 12, 1927. Serial No. 225,636.

My invention relates to that class of devices intended to afford a visible indication of the progress of a game of football or other athletic contest or the like either as 5 an adjunct to the usual score board which is ordinarily placed near the playing field to assist the observers when viewing the game, or to enable a visible record of the game to be made when the progress of the game 10 is being reported by radio or telephone to the operator of the device.

Various devices have hitherto been suggested for this purpose but so far as I am aware they are all open to the objection that 15 as the object representing the ball is moved from one position to another on the background representing the field of play no record is left of its previous position; consequently while at any given instant the 20 position of the ball on the field is visibly indicated to the observers there is nothing to show the course which the ball has taken during the preceding period of play. Additionally, it frequently happens that the 25 observers are interested in noting the performance of the different players on the team and to this end it is desirable that a visible indication be given of the ground gained by each player as he carries, kicks or 30 otherwise moves the ball during the game as well as of the various types of plays employed in such manner that a permanent record thereof may be maintained for as long as may be desired, which will ordinarily 35 be from the start to the finish of the game. Such a record contributes materially to the enjoyment and interest of the observers and enables them to follow the game much better as is indicated on the device 40 than is the case where, as in the devices hitherto employed and to which I have referred, no such relatively permanent and detailed record is made but the ball or other indicating object merely moved about from 45 place to place on the field, and, in some instances, the name of the player and character of play momentarily displayed when or just after a given play takes place and 50 then changed upon or following the ensuing play.

The principal object of my invention therefore is to provide a device by means of which the progress of a game of football or the like may be visibly indicated as the 55 game progresses in such way that a com-

plete record of the consecutive movements of the ball from the beginning of the game until the end thereof will be afforded together with an indication of the character or type of plays by which the ball is moved 60 about and of the players responsible therefor, so that the observer at any given moment during the game will have before him a substantially complete graphic record of the game up to that time and can thus 65 readily note therefrom numerous facts relating to the game such, for example, as the types of play by which the most ground has been gained or lost, the players responsible for the maximum gains or losses and other 70 matters of similar nature which contribute to the intelligent understanding of the progress of the game and consequently enhance the interest of the persons who are observing the indicating device. 75

Further objects of the invention are to provide an indicating device of the character of that to which reference has just been made which is simple, relatively inexpensive and readily operable for its intended 80 purpose; which may be constructed in various sizes so as to adapt it for use under different conditions, as for example, for outdoor use in which case the device is made of such size that the record of the various plays 85 thereon may be readily observed from a considerable distance, or in smaller sizes suitable for use in an auditorium or club or in even still smaller sizes for home use. 90

Other objects and novel features comprehended by the invention are hereinafter more particularly referred to or will be apparent from the following description of certain forms thereof as illustrated in the accompanying drawing. 95

In the said drawing Fig. 1 is a top plan view of one form of the invention in which for convenience the board on which the field of play is indicated is represented as divided longitudinally into upper and lower sections 100 on which, respectively, are represented two methods of indicating the progress of the same game as hereinafter more fully explained; Fig. 2 is an enlarged fragmentary detail plan view showing a portion of the 105 face of the board and certain of the indicating means disposed thereon, while Fig. 3 is a section on line 3-3 of Fig. 2. Figs. 4 and 5 are respectively fragmentary plan views showing different forms of indicating 110

tapes which may be utilized in recording the progress of the game.

In accordance with the present invention I provide a board of suitable size on one face of which is drawn a representation of a football field. This board 1 may be of any suitable material, the selection of which will frequently depend upon the nature of the use to which the device is to be put. Thus, 10 for example, if the device is to be permanently installed outdoors near a football field or stadium with the intention that it shall be observed by the spectators at the game, the board must necessarily be of large size 15 and will thus ordinarily be constructed of suitable lumber while, on the other hand, if it be intended for home use and thus of a size which may be conveniently laid on a table or even held in the lap or in the hand 20 it may desirably be constructed of plywood, wall board or other like material preferably of such a character that it will not readily bend or warp. The diagram representing the playing field is painted, drawn or otherwise produced on the face of the board 25 and may include the goal lines 2, 2' adjacent the ends of the board, representations 3, 3' of the goal posts, and the playing field *a—b—c—d* itself which may be subdivided 30 by equidistantly spaced transversely extending yardage lines parallel to the lines *a—c* and *b—d*. It is ordinarily desirable that as many yardage lines be employed as conveniently may be so that the intervals between them will denote a relatively small 35 number of yards or even a fraction of a yard yet without bringing the lines so close together as to cause confusion or make them appear indistinct at the distance from which 40 they will ordinarily be observed; therefore on a relatively large board a sufficient number of yardage lines may be drawn so that the intervals will represent one half a yard or one yard but where the overall dimensions of the board are relatively small it is 45 preferable to use fewer yardage lines and consider the intervals between them as representing five yards as in the drawing or even a greater number.

50 For indicating the progress of the ball during the game suitable tapes T are removably secured to the board and for this purpose the latter is provided with a plurality of permanently positioned pins 5 55 which project outwardly from its face and are arranged at suitably spaced intervals on the board. While these pins may be of any suitable construction I prefer to employ relatively sharp pointed headed tacks or 60 nails of such length that when driven through the board from the back thereof their points will project for a relatively considerable distance above its face, substantially as shown in Fig. 3. If desired, in 65 order to give a neat finish, a sheet of any

suitable covering material 6 may be secured to the back of the board after the pins are placed in position.

As many pins are disposed at equal intervals on each yardage line as conveniently may be without getting the intervals between them too small and thus the number of pins on each line will ordinarily vary in accordance with the size of the board, a greater number of pins being used on a 70 large board than on a small one. Also where enough yardage lines are used so that the intervals between them indicate a yard or a fraction thereof, the pins will ordinarily be disposed on the yardage lines only 75 80 but where the yardage lines are spaced to indicate five or ten-yard intervals it is desirable, as shown in Fig. 1, to place a row of pins 5' midway between each pair of yardage lines with the pins in longitudinal 85 alignment with the pins 5 in the latter.

As stated, in scoring the game use is made primarily of suitable tapes which are of different colors so as to represent the opposing teams or differently colored on opposite sides for the same purpose; thus when a tape of the latter character is employed, a given side thereof when turned outwardly toward the observer will represent one team, while the other side when so turned will 90 represent the other, thereby avoiding the necessity of using two separate tapes of different colors. As the game progresses, the tape or tapes are stretched between the different pins in accordance with the movements of the ball and in such manner as to show which team is carrying the ball and, also, under certain conditions, in such a way as to indicate the particular kind of play by 95 which the ball is moved. Furthermore, to 100 indicate points at which the ball is brought to rest at the conclusion of each play, or "downed" as it is termed in football, suitable markers may be disposed on the pins, for example, circular markers 7 which may consist of discs of paper, celluloid or other suitable material having a central hole adapted to snugly receive the pin when the marker is placed thereon. To indicate particular types of plays other forms of markers may be employed in conformity with a predetermined system; thus, for example, a marker 8 having a plurality of points may be employed to indicate a penalty and another form to indicate an offside kick, still 110 another form to indicate a forward pass and so on as will be readily understood. For indicating the player by whom the ball is carried or kicked or otherwise moved, a smaller disc 10 having the player's number 115 displayed thereon may be utilized; while these "player's markers" may be of any shape I prefer to make them substantially circular save at one point where they may be provided with a radially outwardly ex- 120 125 130

tending tab 10' which is pierced for the passage of the pin similarly to the other markers. Thus when the player's marker is placed over one of the principal markers it 5 is readily distinguishable from the latter; preferably the players' markers are colored to correspond with the tapes representing the team to which the player belongs.

When employing boards of relatively 10 large size I prefer to utilize paper tapes suitably colored as aforesaid which are conveniently wound in rolls so that after a length of the tape is positioned on the pins it may be torn off from the body of the roll and 15 left in position on the board. Preferably when using tapes of this character dotted, broken or zig-zag lines or marks of other character designed to indicate different types of plays may be printed or otherwise 20 displayed on the tape as in Fig. 4 which illustrates a portion of tape having a zig-zag line printed thereon.

For use with boards of smaller sizes, however, I prefer to employ a continuous tape 25 of woven fabric or the like differently colored on opposite sides as previously explained and instead of tearing or cutting off a length of the tape to designate each play as in the case of the paper tape, to carry it 30 from one pin to another as may be required from time to time, turning the tape over when necessary so that its exposed face will indicate the team in whose possession the ball may then happen to be. Such a fabric 35 tape may be either sufficiently loosely woven to permit it to be readily thrust down on the pins or else, as shown in Fig. 5, provided with suitably spaced eyelets 40 adapted to slip over the pins and maintain the tape thereon.

As an example of one method of using the device, I will now describe the scoring of a consecutive series of plays from the beginning of an imaginary game of football when 45 using, as illustrated on the upper part of the board as shown in Fig. 1, a continuous fabric tape differently colored on opposite sides as the principal indicating medium. Assuming the "red" team is defending the 50 right hand goal and the "white" team defending the left hand, and that the former is given the ball at the beginning of the game, the red team kicks off from its own 55 40-yard line to the 15-yard line of the white team. As soon as this kick is made the operator, preferably beginning at the uppermost pin on the red team's 40-yard line, stretches the tape from that pin to the corresponding pin on the white team's 15-yard line and 60 then places a "down" marker on that pin, of course keeping the side of the tape which denotes the red team outwardly. To show that this movement of the ball has been a kick, the tape may have printed thereon a 65 dotted line or when using a fabric tape a

dotted appearance may be given thereto by placing on the pins along the tape at suitable intervals a plurality of small preferably rectangular markers 13 which are the same or contrasting color as the face of the 70 board 1, thus giving to the tape a broken or dotted appearance, as the markers at a little distance are either substantially indistinguishable from the background or in sharp contrast therewith and with the tape. To 75 indicate that the ball was kicked by player 6, for example, a player's disk with the proper number thereon may be placed on the pin on the 40-yard line where the ball was put into play, while a player's disk giving 80 the number of the player who caught the ball, for example 7, may be placed on the pin to which the tape is attached on the 15-yard line. The ball being now in possession of the white team, it is put into play on 85 the 15-yard line and carried to the 20-yard line by a short run; it is there downed, then carried forward 2½ yards and again downed, and then carried forward 5 yards. To denote these several plays the tape is 90 reversed at the pin on the 15-yard line, brought down to a lower horizontal row of pins and then run in the opposite direction and "down" and "player's" markers placed on the pins at the proper points so as to indicate 95 the number of yards the ball was carried in each play and the number of the player who carried it; to avoid confusion, however, on account of the necessarily small scale of Fig. 1 the "players'" markers are 100 not shown for these and subsequent plays as the manner of using them will be clear from the foregoing. The next play, a punt by the white team carries the ball to the red team's 45-yard line, and to indicate this 105 the tape may be zig-zagged from the point where it was punted to such 45-yard line. At this point the ball, of course, passed into the hands of the red team who immediately punt in the opposite direction to the white 110 team's 15-yard line so that the tape, reversed so as to indicate the red team, is zig-zagged down in the opposite direction to the proper point to denote this punt and "down" and player's" disks placed on the proper pins 115 as already described. The white team being now again in possession of the ball, carry it toward the red goal for a distance of 5 yards, indicated by again reversing the tape and stretching it toward the red goal for 120 the proper distance. Following this play, however, the white team receives a 10-yard penalty for some infraction of the rules and the same is indicated by running the tape back for 10 yards and placing a "penalty" 125 marker 8 over the tape. On the next play, No. 9 of the white team carries the ball by a long run to the 12½-yard line of the red team and in the ensuing plays the ball is carried over their goal line; these several 130

plays are indicated by stretching the tape between the proper points and properly positioning "down" and "player's" markers on the pins. The ball is then brought out from 5 behind the goal line to the red team's 10-yard line and from there a goal is kicked by the white team as indicated by placing the rectangular markers 13 at intervals over the tape so as to give the dotted effect and 10 thus represents a "kick."

While the foregoing is merely illustrative of a series of assumed plays during an imaginary game it is believed that the method of carrying the tape from one pin 15 to another on the board and reversing it where necessary to indicate a change of possession of the ball will be readily apparent as well as the use of different kinds of markers to indicate different types of plays, 20 penalties or other incidents in the game so that a continuous record of the latter is produced on the board which is entirely intelligible to an observer familiar with the system of notation employed and which, of 25 course, is capable of considerable variation and elaboration in conformity with the amount of information which it is desired to afford.

Substantially the same method of scoring 30 may be employed when paper or other tapes are used which may be torn off after they have been stretched to indicate a given play and upon the faces of which suitable notations may be printed to conveniently indicate the character of the play.

The use of such tapes is indicated on the lower half of the board shown in Fig. 1, the same series of plays being there illustrated as has been previously described. 40 Thus, the ball being kicked off from the red team's 40-yard line by that team and downed on the 15-yard line of the white team, a tape of proper color to denote the red team and having a dotted line thereon 45 to denote a kick is stretched between the proper points; the plays by which the ball was then carried by the white team are denoted by using a plain tape of the proper color and the following punt from the white 50 team's 27½-yard line to the red team's 45-yard line by a tape having a zig-zagged line displayed thereon and so on, it being thought that the manner of indicating the subsequent plays will be evident without 55 further description.

It is to be understood that when the paper tapes are employed they will ordinarily be torn off at the proper points after they have been placed on the pins and that the markers 60 are preferably so arranged as to frictionally engage the pins and thus assist in holding the tapes in position when they are superimposed thereon.

It will further be appreciated that it is 65 ordinarily desirable to commence the scor-

ing of the game as near the upper edge of the board or field as may be convenient and to continue the record of the plays toward the bottom edge of the board as the game progresses substantially as shown in the 70 drawing. It is thus unnecessary to make the field *a—b—c—d* on the board of the same width in proportion to its length as a regular football field which is ordinarily 100 yards long; in fact, it is frequently desirable in order to give ample room for the scoring of the game to increase the relative width of the field *a—b—c—d* in proportion to its length. Moreover, if desired, the board may be provided with more than one 80 field and each field used to score a definite period of the game such as a "quarter" or a "half" or two or more boards employed for the scoring of the full game by utilizing each of them for a definite period thereof. 85

After the game is finished, the tape, if in continuous form, as well as the markers may be readily removed from the pins and utilized for scoring a subsequent game but if paper tapes have been employed these will ordinarily be thrown away and only the markers preserved for subsequent use.

It will thus be apparent that by the use of my invention a visible record of the progress 95 of the game and of numerous facts incidental thereto such as the types of plays, names of players and the like may be readily made as the game progresses and preserved for as long as desired so that at any 100 period of the game the observer will have before him a full and complete record of the game as far as it has then progressed.

Moreover, it is to be understood that while I have referred more particularly to the use 105 of metallic pins as supporting means for the tapes as the same are convenient and well adapted for this purpose, other equivalent means may be employed therefor if desired, and other changes and modifications made 110 in the details of construction and arrangement of the various parts without departing from the spirit and scope of the invention as defined in the appended claims.

Having thus described my invention, I 115 claim and desire to protect by Letters Patent of the United States:

1. In a device for forming a visible record of the progress of a football game or the like, the combination of a board having displayed thereon a representation of the playing field, a plurality of pins disposed at regularly spaced intervals over the face of the board and projecting thereabove and forming a part thereof and a tape adapted to be selectively positioned and supported on said pins to extend from different points on said board to other points thereon to thereby denote the course of the ball during the game. 120

2. In a device of forming a visible record 125

of the progress of a football game or the like, the combination of a board having thereon a representation of the playing field, a plurality of pins permanently disposed on said board in transversely extending symmetrically spaced rows, projecting above the face thereof and permanently secured thereto and a flat tape adapted to be stretched from one of said pins to another and supported thereupon to thereby give a graphic representation of the movements of the ball during the game.

3. In a device for forming a visible record of the progress of a football game or the like, the combination of a board having thereon a representation of the playing field, a plurality of pins disposed on said board in transversely extending spaced rows and permanently secured thereto, a tape adapted to be stretched from one of said pins to another and supported thereupon to thereby give a graphic representation of the movements of the ball during the game and markers adapted to be positioned on the pins in superimposed relation to the tape to afford a graphic representation of incidents of the game in accordance with a predetermined system.

4. In a device for forming a visible record of the progress of a football game or the like, the combination of a board having thereon a representation of a playing field, a plurality of pins arranged at spaced intervals in parallel rows running transversely of the field, said rows being equidistantly spaced from each other and the points of the pins projecting above the face of the

board and a tape differently colored on opposite sides to denote the opposing teams and adapted to be stretched between and supported on said pins selectively to afford a graphic representation of the movements of the ball during the game and to indicate the team by which each such movement is effected in accordance with the face of the tape which is turned outwardly as it is displayed on the board.

5. In a device for forming a visible record of the progress of a football game or the like, the combination of a board having thereon a representation of a playing field, a plurality of pins arranged at spaced intervals in parallel rows running transversely of the field, said rows being equidistantly spaced from each other and the points of the pins projecting above the face of the board, a tape differently colored on opposite sides to denote the opposing teams and adapted to be stretched between and supported on said pins selectively to afford a graphic representation of the movements of the ball during the game and to indicate the team by which each such movement is effected in accordance with the face of the tape which is turned outwardly as it is displayed on the board, and markers adapted to be positioned on said pins in superimposed relation to the tape to indicate incidents of the play in conformity with a predetermined system of notation.

In witness whereof I have hereunto set my hand this 10th day of October, 1927.

JOSEPH M. HARTLEY.
